UNITED STATES PATENT OFFICE

162,401

INFANT'S TOILET SEAT

Sheldon B. Glass, Chicago, Ill.

Application September 25, 1950, Serial No. 12,331

Term of patent 14 years

(Cl. D4—5)

To all whom it may concern:

Be it known that I, Sheldon B. Glass, a citizen of the United States, residing at 914 Diversey Parkway, Chicago, Illinois, have invented a new, original, and ornamental Design for an Infant's Toilet Seat, of which the following is a specification, reference being had to the accompanying drawings, forming a part thereof.

I claim:

The ornamental design for an infant's toilet seat, substantially as shown.

SHELDON B. GLASS.
